United States Patent Office.

JAMES H. MURRILL, OF BALTIMORE, MARYLAND, ASSIGNOR TO HIMSELF,
LEWIS R. KEIZER, AND JACOB SEEGER, OF SAME PLACE.

Letters Patent No. 76,936, dated April 21, 1868.

IMPROVEMENT IN MACHINES FOR CUTTING BUNGS.

The Schedule referred to in these Letters Patent and making part of the same.

TO ALL WHOM IT MAY CONCERN:

Be it known that I, JAMES H. MURRILL, of Baltimore, in the county of Baltimore, and in the State of Maryland, have invented new and useful Improvements in Machines for Cutting Bungs; and do hereby declare that the following is a full, clear, and exact description thereof, reference being had to the accompanying drawings, and to the letters of reference marked thereon. In the annexed drawings making part of this specification—

A represents a metallic frame or table, which is supported upon the legs A'. Upon the upper side of this table, at its front end, is secured a plate, C', which has cast upon its upper side a standard, and upon the upper end of this standard is cast a cylindrical collar, B. Inserted in the horizontal cylindrical opening in this collar is a cylinder, C, which has a square hole made through it longitudinally.

On one end of the cylinder C is secured a gear-wheel, B', which gears into a wheel, J, on shaft I. The shaft I lies parallel with frame A, but above it, being supported and having its bearings in the uprights Z Z, which are secured to the side of the frame. This shaft I is provided with the graduated pulleys J', and the gear-wheels J and I'.

D represents a plate which is secured upon the frame A, and which has its two ends D' D' turned up, so that they will support and supply bearings for a hollow cylinder, E, and a horizontal shaft, V. Upon cylinder E, near one end, is secured a gear-wheel, F, which meshes into the wheel I, and by which is is driven. The cylinder E is surrounded by a collar, E', which is grooved upon its periphery, and which is fitted so that it will slide upon the cylinder. This cylinder is provided with three long slots made longitudinally of it, and equidistant apart. G G represent feeders, which consist of metallic straps or strips, with teeth made in one end, while their other ends are secured fast to the collar E'. These feeders have their toothed ends to pass through the long slots in the cylinder. Lying close to plate D is guide-rod G', which has secured to it two arms H', which take into the groove in collar E', and also a rack-bar, H. This guide-bar moves endwise, and by means of it the collar E' is caused to slide upon the cylinder E, moving with it the feeders G.

X represents a vertical shaft, which is held in bearings secured to the side of the frame A. This shaft is provided with a crank-handle, and with a gear-wheel, x'; which gears into the rack-bar H, and is surrounded with a coiled wire spring, d. One end of this spring is secured to a clutch-collar, p, while the other end is secured to the shaft X, and thus serves to revolve the shaft in one direction, while its crank-handle serves to revolve it in the other.

Upon one end of the cylinder E is secured a wheel, K, which is formed so that it will not obscure the opening through the cylinder. This wheel has in its face three equidistant grooves, in which are placed the slides a a a, the inner ends of which are toothed, and project into the hole in the wheel, which corresponds with that of the cylinder. These slides are regulated by the set-screws e e and the springs i i, so that they will yield endwise to accommodate themselves to the size of the wood which is passing through the cylinder.

The shaft V, which has previously being adverted to, is provided with a pulley, V', and at one end with a head, W', to which is secured a series of cutters, W W.

Upon the frame A, at its rear end, is placed a sliding frame or carriage, L, which has erected upon it supports L' L', in which the horizontal shafts M and T have their bearings. Shaft M has secured to it a circular saw, N, and a pulley, P, while the shaft T has secured to it a pulley, S, and the cutters T' and u.

The carriage L slides in dove-tailed grooves crosswise of the frame A, and is caused to slide backwards and forwards by a screw, O, which is provided with a crank-handle, O'.

At the rear end of the frame A is erected a standard, l, which has secured or formed upon its upper end a sleeve, Q, and through this sleeve passes a rod, Q', which is pointed, so as to act as a centre at its forward end. Surrounding the rod Q', at the rear end of sleeve Q, is a coiled-wire spring, t, which forces said rod in one direction, while an inclined plane, from n to n on the strap R, forces it in the other. The bar f has a hole in it,

through which the rear end of rod Q' passes, and said bar acts against the spring t , while the inclined plane, at n , acts upon it. b is a guide-pin, which is secured to bar f , and it is surrounded with a spring to force it outward after having been forced inward by the inclined plane at n . h represents a set-screw in the upper end of bar f , which acts upon the rod Q' , when desirable.

The operation of this machine is as follows: When bungs are to be made of lumber not already prepared, the lumber is first sawed into square strips of any desired length, so that they may be passed through the square hole in cylinder C . A suitable rest is prepared for the outer end of the strip, to guide it and hold it in proper position.

The strip is first fed in by hand until it is caught by the feeders G . The hand of the operator can then be removed, and the feeders G do the work of feeding. Belts pass from a counter-shaft above the machine to the pulleys on shafts I , V , M , and T , and give them suitable motion. The wheels I' and J give motion through wheels F and B' to the cylinders C and E , causing them to revolve in their bearings.

It will thus be seen that the strip of timber is kept revolving while it is passing through the machine. As the forward end of the strip emerges from cylinder C , the cutters W on shaft V , revolving rapidly, commence work upon it, and, cutting its corners off, speedily round it. The stick passes then into the cylinder E , where it is caught between the feeders G . The operator then, by turning shaft X to the right, moves the collar E' , and with it the feeders and rounded stick, causing the forward end to pass through wheel K , and toward the point of rod Q' . When it reaches the point of this rod, the cutters T' on shaft T act upon it and cut it in a tapering form, such as bungs have, while the cutters u act upon its edges at its end, rounding it suitably. The operator now turns the crank-handle O' to the left, causing the plate L to move, and with it the circular saw N , so that it, the saw, will sever the bung from the stick.

The bung being cut in proper shape, the operator turns the crank-handle O to the left, causing the circular saw to move up and sever the bung from the stick. Before the saw has severed the bung, the point of rod Q' is forced back by the spring t to follow the inclined plane n of the bar R , thus releasing the bung, and allowing it to drop to the floor the instant it is severed, thereby avoiding all danger of the saw jamming before it performs its work. The point of the rod Q moves back simultaneously with the advance movement of the saw, and moves up again as the saw recedes, and is in its proper position to receive the stick for the next bung.

The operator now, by shaft X , throws back collar E' and feeders G , so as to catch a fresh hold on the stick, the toothed ends of slides a resting against and holding the stick in the mean time.

When the stick is again moved forward, the operation of tapering, bevelling, cutting off, and dropping the bung is the same as has before been described.

The cutters T' are made long enough to cut the largest, or, rather, longest bungs in use. The set-screw g regulates the size of the bung by setting the plate or carriage L with reference to the stick as it issues from wheel K .

Having thus fully described my invention, what I claim as new, and desire to secure by Letters Patent, is—

1. The arrangement of the collar E' with its spring-feeders G that lie in the slots of the cylinder E , and are operated to carry the stick through the cylinder after being rounded by the cutters, substantially as specified.

2. The wheel K provided with the slides a , and placed on the end of the cylinder E for gripping the stick while the bung is being formed, substantially as specified.

3. The arrangement of the sliding frame L , with shafts T and M placed opposite to each other, one provided with the cutters T and u , and the other with the saw N , whereby the bung is formed, cut from the stick, and dropped, in the manner substantially as specified.

4. The arrangement of the adjustable rod Q' in the sleeve Q , supported by the bars f , and in combination with the inclined bar R on the end of frame L , whereby the bung is held and dropped, the whole arranged to operate substantially as specified.

In testimony that I claim the foregoing, I have hereunto set my hand, this 28th day of January, 1868.

JAS. H. MURRILL.
